CLAIM

The ornamental design for a bench as shown and described.

DESCRIPTION

FIG. 1 is a top front perspective view of a bench showing the claimed design;

FIG. 2 is a front view thereof;

FIG. 3 is a rear view thereof;

FIG. 4 is a left side view thereof;

FIG. 5 is a right side view thereof;

FIG. 6 is a top view thereof; and

FIG. 7 is a bottom view thereof.

The figures are illustrated to show contrasting appearance. The gray-shaded portions of the bench have a different appearance from the portions of the bench with a wood-grain pattern.

The portions of the bench with a wood-grain pattern have a wood appearance.
